UNITED STATES PATENT OFFICE.

ALFRED LEHNER, OF KELSTERBACH, GERMANY, ASSIGNOR, BY MESNE ASSIGNMENTS, TO EASTMAN KODAK COMPANY, OF ROCHESTER, NEW YORK, A CORPORATION OF NEW YORK.

PHOTOGRAPHIC SCREEN AND PROCESS OF MAKING THE SAME.

1,112,540.

Specification of Letters Patent.

Patented Oct. 6, 1914.

Application filed February 15, 1909. Serial No. 478,036.

To all whom it may concern:

Be it known that I, Dr. ALFRED LEHNER, citizen of Switzerland, residing at Kelsterbach-on-the-Main, Germany, have invented 5 certain new and useful Improvements in Photographic Screens and Processes of Making the Same; and I do hereby declare the following to be a full, clear, and exact 10 description of the invention, such as will enable others skilled in the art to which it appertains to make and use the same.

This invention relates to the art of multi-color screens such as are used in color photography. Where these color screens or filters have been produced by parallel or cross-hatching this has hitherto always been done by printing the lines on plane surfaces or sheets. These lines, according to the nature of the process, serve either to mask or 20 to prevent the passage of the color rays, where they occur, or they may be of the various colors desired and of such a nature as to permit the passage through the screen of only the corresponding color rays where 25 they occur. In the latter case, as is well-understood, the picture printed in the various colors must be colored with such intensity that sufficient absorption of the complementary rays occurs. In view of the 30 fineness and the thinness of the lines which are thus printed on the screen sheet and in view of the necessity of maintaining such lines transparent, it has been found impossible hitherto to attain the necessary color- 35 intensity for these lines to produce effective color screens for multi-color photography.

Where the lines printed on the surface serve merely as a color resist to mask the sheet, where they occur, against the action 40 of the color or dye with which the sheet is to be afterward treated, the difficulty just mentioned does not arrive, but there still remains the objection common to all printing methods in this art, hitherto known, 45 that it is difficult to obtain the printed lines of resisting material distributed evenly and sufficiently sharp. These lines are usually very uneven, presenting contracted and expanded portions so that on coloring the 50 surface thus hatched with the resist, a serviceable color screen can not be obtained.

It is the object of the present invention

to remove these objections and at the same time to devise a process for this purpose which is both simple and inexpensive and 55 can be readily carried out.

In order to attain this object my invention consists in the method and features now to be described and then pointed out in 60 the claims.

In order to aid the description reference is had to the accompanying drawing in which—

Figure 1 represents a transverse section on an enlarged scale of a screen sheet at 65 one stage of one method embodying my invention; Fig. 2 a similar view of the same at a further stage of the method and Fig. 3 a diagrammatic plan view of a screen sheet treated according to a modified 70 method, involving my invention.

For producing two-color screens according to this invention I proceed in the following manner: A thin sheet or foil of suitable 75 moldable plastic material, such as celluloid or other photographic plastic substance is pressed into intimate contact with a metallic die having the requisite hatching formed in relief on its plane surface, heat being employed in connection with this pressing 80 operation. Either the die or the plastic sheet or both may be heated for this purpose, as will be well-understood by those skilled in the art of molding celluloid and similar plastic substances. The metal 85 relief die for this purpose may be prepared by any suitable method, such for example as ruling the same with an acid resist and etching the surface. By this compression and concurrent heating an intaglio copy of 90 the relief hatching on the metal surface or plate is produced in the celluloid sheet. This intaglio hatching is indicated in Fig. 1 of the drawing, which represents a greatly enlarged transverse section of a portion of 95 the celluloid sheet provided with the said hatching. The recesses *b* correspond to the relief hatching on the metal plate, while the elevations *a* correspond to the recesses on the same. This hatched celluloid sheet is 100 thereupon inked in with printers' ink or varnish; in a manner well known in the art of printing, such as by rolling over the same a printer's inking roller. Thereby only the

elevations *a* receive the ink or varnish or other resist, as indicated at *c* Fig. 2. The back of the sheet having been sufficiently protected by a suitable resist indicated by *z* in Fig. 2, the said sheet is now immersed in a color bath, such as a concentrated solution of a dye in alcohol for a short time, whereby the recesses or depressions *b* receive the color, as at *d* Fig. 2, while the rest of the surface of the sheet repels the dye or bath.

By suitably regulating the time of immersion and the degree of the concentration of the bath, any desired intensity of color on the exposed portions of the sheet may be obtained and the color can be uniformly applied.

The sheet having been dried, the resist on the elevations *a* and on the back of the sheet is removed with a suitable solvent, such as oil of turpentine and the elevations are now suitably colored. This may be done in a simple manner by passing over the sheet a roller covered with fine cloth or other textile and impregnated with an alcoholic dye solution. The elevations *a* may by this method be colored differently from the depressions or recesses *b* and the two colors can be so selected as to produce a two color screen suitable for use in color photography in a manner well-understood.

In order to reduce the fluidity of the alcoholic color solution employed, a thickening agent soluble in alcohol, such as resin, may be added thereto. In this manner an accurate and effective two-color screen may be obtained without difficulty.

To produce three-color or four-color photographic screens I proceed as follows: I produce parallel hatching in relief on the plastic transparent sheet in the manner above described for two-color screens and I color the intaglio lines *b*, in the manner described by covering the relief lines *a* and the back with a color resist or mask and then immersing in a color bath, for example in a solution of rhodamin. The resist is then removed and the surface of the celluloid or other plastic sheet provided with the parallel hatching is again pressed onto the metallic hatched die while being heated, the sheet being so placed, however, that its hatchings form an angle, preferably a right angle, with the hatchings on the metallic die. Thereby the surface of the celluloid or other plastic sheet is covered with a series of parallel hatchings in relief as in the first part of this method, but these hatchings now are at an angle, preferably a right angle, to the position of the first series of hatchings. I now cover the relief portions or ridges and the back of the sheet with a resist and again immerse the same in a color for example malachite green. On again removing the resist a reticulated color

screen is obtained in which one set of lines or bands have been applied in red while the other series of lines, crossing the first, is applied in green. If the breadth and the distance between the bands of the two series have been made equal to each other, a color design will appear on the surface of the screen sheet which is represented in Fig. 3, in which one-fourth of the quadrangular stiples are green, these stiples being represented at *e* and one-fourth, represented at *f*, red. The quadrangular stiples or patches *g* which occur at the crossing points of the two-color bands will be nearly black if the colors have been properly chosen. A fourth portion of the surface consisting of portions *h* of the elevated lines or ridges will be without color. To these elevated white portions the required third color is then applied by coating the surface of the sheet with a layer of actinic material producing the desired color on exposure to light. Such a material is bichromatized gelatin or isinglass or bichromatized casein. Having applied a coating of such materials in the usual and well-known manner on the hatched surface, the back of the sheet is exposed to the light and then developed with water in the known manner. Thereby the third color is produced on the screen.

The black or the dark stiples or quadrangles occupying one-fourth of the surface of the screen and which are due to the superposition of two colors do not interfere with the production of pictures having bright and glowing colors. This has been shown by practice. This is probably due to the extreme transparency of the celluloid which is employed in thin layers or films and to the colors employed. Should it be desired, however, to avoid this production of black or substantially complete light absorbing portions at the points of intersection of the color bands, this object may be attained by a judicious selection of the colors and the consequent production of a four-color screen. For example if we select a four-color system employing the colors red, orange, yellow and blue-green, one series of bands will be made yellow and the series of color bands crossing the same will be made red. In all other respects the method above described for the three-color system will be followed in this method. The colors of the quadrangular patches at the intersection of the two series of color bands will now be orange, instead of black or substantially colorless, as it would be under the three-color system above described. The color for the fourth series of stiples of color patches is then produced in the manner set forth for the three-color method, namely by the exposure of an actinic color producing film to light passing through the screen film or sheet. According to this last method when

using celluloid as the screen film it is necessary to employ alcoholic color baths for the first two applications of color.

In order to employ colors or dyes soluble in water it is necessary to apply to the surface of the celluloid a coating of a substance adapted to receive aqueous or water dissolved dyes. Examples of substances well adapted for such coatings are gelatin, casein and the like. In this manner any plastic or moldable substance may be employed as a screen sheet, though the same will not directly receive color, if only the same possesses sufficient transparency. To make such a sheet adapted to receive the desired colors it is only necessary to coat the same with a thin layer of a color receiving substance, gelatin, casein or the like for aqueous coloring baths or pyroxylin for alcoholic color baths.

Since the color lines or stipples in the color screens prepared as hereinbefore described are in different planes the screen sheet is finally compressed between plane surfaces heated coincidentally, whereby the relief color portions are made flush or substantially flush with the depressed portions and a practically or wholly flat multicolor screen results.

30 While in the processes described above the color in the initial coloring steps is applied by immersing the screen sheet in a color bath, it is possible to apply such color with a brush previously dipped in a color solution, in which case it is not necessary to cover the back of the screen sheet with a resist. Although I consider the immersing step the preferable one I am not confined to the same for purposes of this invention.

40 It will be noted from the above that a multicolor screen made under my invention consists of a sheet of any suitable material, such as cellulose material or other plastic material which is faced with variously colored areas. On this screen one or more of the colors are arranged on relief portions of the sheet, integral with said sheet, and which are compressed to be substantially flush with said sheet material.

50 What I claim and desire to secure by Letters Patent is—

1. In the art of preparing multicolor screens for color photography, the process which consists in coating the relief portions of a relief hatched screen sheet with a color resist, then applying color to the intaglio portions of the sheet and then removing the resist.

60 2. The process of preparing screen sheets having relief portions thereon for color photography, which consists in coating the relief portions of said sheet with a color resist, then applying color to the surface thereof and then removing the resist.

65 3. The process of preparing multicolor

screens for color photography, which consists in coating the relief portions of a relief hatched screen sheet with a color resist, then applying color to the surface of the screen sheet, removing the resist and coloring the relief portions. 70

4. The process of preparing multicolor screens for color photography, which consists in hatching a screen sheet in relief, coating the relief portions with a color resist, then applying color to the surface of the screen sheet, then removing the resist and coloring the relief portions. 75

5. The process of preparing multicolor screens for color photography which consists in coating the relief portions and the back of a screen sheet with a color resist, then immersing the screen sheet in a color bath, then removing the resist and coating the relief portions with a color different 80 from that in the color bath. 85

6. The process of preparing multicolor screens for color photography, which consists in hatching a screen sheet, provided with relief hatching and colored intaglio 90 hatching, in relief and at an angle to the first system of hatchings, coating the resultant relief portions with a color resist, then applying color to the surface, removing the resist and coating the surface of the screen with an actinic substance capable of producing the desired color under the action of light, and then exposing the screen sheet to light passing through the back of said screen sheet. 95

7. The process of preparing multicolor screens for color photography, which consists in covering the relief portions of the surface of a screen sheet hatched in relief with a color resist and applying color to the surface, then removing the resist and forming relief hatching on the said surface with a color resist at an angle to the first system of hatching again covering the relief portion of the surface with a color resist and applying another color to the surface, then removing the resist and coating the surface with an actinic substance capable of producing the desired last color under the action of light and then exposing the screen sheet to light passing through the back of said screen sheet. 105 110 115

8. The process of preparing multicolor screens for color photography, which consists in covering the relief portions and the back of a relief hatched screen sheet with a color resist and immersing the screen sheet in a color bath, then removing the resist and relief hatching the surface at an angle to the first system of hatching, again covering the relief portions and back with a color resist and immersing the screen sheet into another color bath, then again removing the resist and coating the sheet with an actinic substance capable of evolving a third color 120 125 130

under the action of light and then exposing the screen sheet to light passing through the back of said sheet.

9. A multicolor screen for color photography consisting of a sheet faced with variously colored areas, the material of the sheet bounding said areas presenting one of the colors being integral with the sheet and compressed to be substantially flush with the surface thereof.

10. A multicolor screen for color photography consisting of a sheet permitting the passage of light, said sheet being faced with variously colored areas, the material of the sheet bounding said areas presenting one of the colors being integral with the sheet

and compressed to be substantially flush with the surface thereof.

11. A multicolor screen for color photography consisting of a sheet of photographic plastic material faced with variously colored material of the sheet bounding areas, the said areas presenting one of the colors being integral with the sheet and compressed to be substantially flush with the surface thereof.

In testimony whereof I hereunto affix my signature in the presence of two witnesses.
